Term of patent 14 years

(Cl. D15—11)

Fig. 1.

Fig. 2.

Fig. 3.

Fig. 1 is a front elevational view of a sofa or similar article showing my new design;

Fig. 2 is a side elevational view thereof; and

Fig. 3 is a fragmentary rear elevational view thereof.

The side of my sofa or similar article opposite that shown in Figs. 2 and 3 is symmetrically reverse but otherwise identical.

The characteristic features of my design reside in the portions shown in full lines.

I claim:

The ornamental design for a sofa or similar article, as shown and described.
